James Camrod Ledbetter, Jackson Heights, Long Island, N. Y., assignor to The Prosperity Company, Inc., Syracuse, N. Y., a corporation of New York

Application January 28, 1929, Serial No. 335,476
Renewed October 3, 1933

17 Claims.

(Cl. 68—9)

This invention relates to presses and particularly to those adapted to press garments and iron laundry work.

An object is to improve garment or ironing presses in respect to the operating means therefor which opens and closes the press jaws by moving one or both jaws but in the embodiment shown the operating means is attached to the head to actuate it in relation to the buck and produce pressure on the work placed therebetween.

Among other things, I have produced a single force applying means for separating or moving one jaw straight away from the other, say the press head from the buck, and also for laterally swinging said head to or from the buck to close and open the press; and as an example of the force applying means there is shown a weight which acts vertically downwardly to separate the press jaws and pulls laterally to impart either a closing or counterbalancing force and movement to the press head and operating means connected therewith. Other force applying or counterbalancing means such as springs or the like may be employed if desired.

The accompanying drawings show an example of the invention wherein:

Figure 1 shows a side view of the press in open position.

Figure 2 shows a side view of the press in closed or partially closed position with the head just above the buck and ready to be moved vertically into contact therewith.

Figure 3 shows a side elevation of the press head closed over and under compression against the buck.

Referring to the drawings, there is shown a frame 5 on which a buck 6 is supported and a press head 7 is adapted to coact with the buck to press or iron the work placed therebetween. The pressing members or jaws 6 and 7 may be heated in any approved manner, and for both garment pressing and laundry ironing work it is usually the practice to pad the buck 6, while for garment pressing alone the head 7 is covered with a press cloth to avoid shining woolens; and for ironing laundry or wash goods the head 7 has its metallic polished face exposed directly to the work to impart a good domestic ironing finish to the wash goods.

Operating means is used to actuate a jaw or the jaws and force applying or balancing means is connected with the operating means to aid the latter to undergo a smooth back and forth action to open and close the press which occurs

when the head is lifted and then carried laterally away from the buck or toward it. A swingable upright 9 has its upper end attached to the press head 7 and in this instance reaches around the rear of the jaws for that purpose and its lower end is directed into the frame and is pivotally mounted below or under the buck on pins on a cross shaft 16. A handle 11 may be extended from the upright 9 over the press head 7 in convenient reach of the operator in front of the press to either draw the head forwardly over the work or throw the head rearwardly as the case may be, depending somewhat on the type of press constructed and depending on the characteristics of the counterbalancing or force-applying means.

The upstanding swingable jaw carrying member 9 may be constructed in one single piece or made in pairs and then spaced in parallel relation to each other to guide the relatively long movable jaw back and forth in relation to and from the buck. The movable supporting pivot 10 in reality possesses a compound motion in that it either rotates or the upright 9 rotates thereon to swing the head open and closed and the pivot 10 also moves vertically to release the jaw compression. The pivot 10 is carried by an operating member or movable supporting means 17 under or below the jaws to operatively support the head 7 and upright 9.

As suggested, a movable supporting member or means 17 is operatively mounted in the press frame, say on a frame pivot 13, and consists of any suitable motor or pedal actuating means to produce jaw compression. In this example of the invention, the prime mover is a pedal 14 made on a lever arm 15. An upstanding link or arm 16 is attached or integrally joined to the pedal and projects upwardly toward the buck. In fact a bell crank 15—16 is formed as the prime mover or motive means to actuate the press, and an arm 17 is integral with the bell crank and by which the latter is pivotally mounted in the frame for bodily up-and-down and swinging motion. The arm 17 affords a compound pivotal or swinging and up-and-down movement, or a two in one motion for swingable upright 9 and jaw 7. Hence the juncture of the bell crank arms 15 and 16, defined by the pivot 10 or the upright 9, possesses the bodily two-in-one motion action in question. The bell crank with the arm 17 and pivots 10 and 13 form pivot means which carries the upright 9 for pivotal and vertical bodily movement.

A substantially vertically mounted link 19 is pivotally suspended from the frame on a cross shaft or pin 20 and the lower end is pivotally con-

nected at 21 to the upper end of the arm 16. The parts 16 and 19 constitute an upright toggle conveniently disposed in the frame where it is out of the way and pressure from any source applied to 5 the power arm 15 causes the bell crank 15-16 to pivot in the frame and causes the fulcrum pin 10 to move downwardly to compress the head 7 against the buck. The toggle 16-19 straightens with a powerful force transmitting movement and 10 locks the head down onto the buck. The toggle is, therefore, locking means for holding the head in closed position. The frame pivot 13 and upright pivot 10 are spaced apart for the purposes just described and to afford vertical movement 15 for the fulcrum point 10 to attain vertical jaw separation or movement.

The pivot 20 includes adjustment means to vertically alter the position of the pivot 10 in relation to the frame or press jaws to regulate the 20 degree of head pressure on the buck. To this end the shaft 20 is made on or carries a cam 23. The shaft 20 is journaled in the press frame and when turned by a wrench placed in a notched wheel 24 which is anchored to the cam 23 and 25 shaft, the cam 23 is of course rotated, and the toggle link 19 being suspended from the cam, it follows that the toggle 15-16 is raised or lowered an amount equal to the throw of the cam. Therefore the compound motion fulcrum 10 or 30 the toggle formed by the links 16 and 19, is adjustably set to effect the proper jaw compression to be exerted by a downward pull through the upright 9. A locking pawl 25 is pivoted at 26 on the frame and has a spring 27 to keep its 35 head seated in the notched wheel to hold the adjustment.

The upright 9 is weighted above by the head 7 and hence is top heavy and once started will fall rapidly to the rear and carry the head with it, 40 hence opening the press. Moreover, the rearwardly and upper arched portion 9^a of the upright 9 is off center to the rear of the pivot 10 and center of gravity of the head 6 and therefore the weight of the arm portion 9^a introduces 45 a rearward gravitational force which initiates or starts the rearward travel of the head. Balancing, counterbalancing or overbalancing means may therefore be introduced to compensate for the unbalanced condition set up by the weight 50 of the head 7 and the arm portion 9^a, as desired. In the present instance the portion 9^a may remain predominant so as to open the press by gravity when compression is released.

A weight suspension support arm or lever 30 55 is pivoted in the frame at 31 and has a loose motion pivotal connection 32 with the toggle 16-19 say at the pivot 21 of the latter and is adapted to transmit or exert a vertical force or lift upwardly on the toggle and hence on the pivot 60 10 and on the upright 9 and press head 7 to separate the jaws after the pressing or ironing operation. A pendulum-like weight 33 is fixed to a pendulum rod or link 34 and this pendulum counter-balancing weight 33-34 is suspended at 65 35 from the lever 30. Hence the dead weight of the pendulum pulls upwardly on the toggle pivot 21 to correspondingly lift the head 7 and remove jaw compression as the toggle 16-19 breaks from its straight line locked pressure position. This vertically applied force is exerted 70 against the vertically disposed links 16 and 19.

Also there is provided a substantially horizontal link or connecting means 36 between pivot connecting pins 37 and 38 operatively joining the upright 9 to the pendulum balancing means 33-34. 75

This link 36 imparts a lateral force to the press head 7 and to its supporting arm or frame 9 to either thrust the head rearwardly from the buck or introduce a balancing factor so that the head 7 will easily draw forwardly to closed position over the buck. It is seen in Figure 1 when in press open position, that the pendulum weight 33-34 is pulling on the head tending to draw it forwardly, but the force exerted by the weight of the head and off-set or arched portion 9^a is a little greater than that of the weight 33 so that the press remains open against the tendency of the pendulum counterbalance 33-34 to return to vertical to restore the press to closed position. The operator lightly pulls on the handle 11 to add just enough force to that being exerted by the weight 33 to overcome the inertia of the press head and any unbalanced weight of the head 7 and upright 9 and start it forwardly, whereupon the operating means 15 is then depressed by foot power or otherwise to straighten the toggle 16-19 and lock the jaws together under compression.

Having completed the period of pressure on the work, kick-off means is actuated to break the toggle which is accomplished by sliding the 25 pin 21 in the slot 32 and in this way the lever 30 is connected to the toggle without hampering the free operation of either the toggle or the lever 30. A kick-off arm 40 is pivoted on the cam shaft 20 and has a side lug 41 which impinges the front 30 edge of the toggle link 19 to thrust it rearwardly. A vertical connecting link 44 extends downwardly and a pin 42 connects each end with its operating elements 40 and 43, the latter being a kick-off pedal 43. The kick-off pedal 43 is in a low 35 position convenient to an operator and thus works the highly located kick-off arm 40 placed where its toggle breaking force is conveniently applied. It is to be noted that the kick-off link 44, the toggle 16-19, the pendulum weight 33-34 and 40 the upright 9 are all substantially upright and this arrangement makes a compact combination.

The force applying elements 16-19 and 36 are disposed at an angle to each other and each element satisfactorily performs its function of applying two independent forces initiated from one force applying means such as the weight 33 or other means in the form of a spring or other motive power. The two forces act at an angle to each other, originate in the one means 33, but 45 perform different purposes as is well understood and there is no interference in the application of the two forces.

Preferably the pendulum 33-34 never quite reaches the vertical as noted in Figures 2 and 3 55 because it is desired that a lateral forward pull be exerted on the head even after the head reaches overlapping position with the buck because that action assures the operator that the head is at its forwardly limited position before he applies 60 the necessary force on the operating member 15 to draw the head down and lift the weight 33. The weight of the pendulum 33 is just sufficient 65 to overbalance and lift the head to relieve the pressure between the jaws. The length of the slot 32 limits the distance through which the toggle breaks and allows it to straighten to proper position and each end of the slot 32 is a stop for the pin 21. No other stop is required.

It is significant that the head and upright 70 constitutes an inverted pendulum 7-9 and the force applying means 33-34 is a simple pendulum. The two pendulums are connected together so that they pull against and counterbalance each other. The pendulum suspension points 10 and 35 75

are correspondingly located, one under and the other above its suspended weight.

What I claim is:

1. A press comprising a frame, a coacting head and buck, an upright having its upper end attached to the head, a bell crank having an arm projecting therefrom, a frame pivot on which the arm is mounted, the lower end of the upright being pivoted on the bell crank in spaced relation from the frame pivot, a link having its upper end pivoted on the frame and its lower end pivotally connected to the bell crank forming a toggle, and means to urge the upright and head upwardly and to counterbalance the same in the pivotal movement of the upright. 5
2. A press comprising a frame, a coacting head and buck, an upright having its upper end attached to the head, a bell crank having an arm projecting therefrom, a frame pivot on which the arm is mounted, the lower end of the upright being pivoted on the bell crank in spaced relation from the frame pivot, a link having its upper end pivoted on the frame and its lower end pivotally connected to the bell crank forming a toggle, means to urge the upright and head upwardly and to counterbalance the same in the pivotal movement of the upright, and kick-off means to open the press including means above the bell crank to exert a breaking force on the toggle. 10
3. A press comprising a frame and a buck carried thereby, a pedal pivoted in the frame, a head, an upright having its upper end attached to the head and its lower end pivoted on the pedal below the buck, an upright arm integral with the pedal at a point spaced from the frame pivot aforesaid and extending upwardly, a link pivoted on the frame under the buck and pivotally connected with the upper end of the upright arm thereby forming a toggle, a toggle breaking arm pivoted on the frame and engaging the upper link to forcibly swing the same, a kick-off pedal pivoted on the frame, and a connection from the kick-off pedal to the toggle breaking arm. 15
4. A press comprising a frame, a head and buck thereon, a bell crank pivoted in the frame and including an upright arm and horizontal arm the latter being pivoted in the frame, an upright head support pivoted on the horizontal arm and attached to the head, an upright toggle link pivoted in the frame and pivotally connected to the upper end of the upright arm, a toggle breaking arm pivoted on the frame proximate the upright toggle to engage and break the latter, a kick-off pedal pivoted on the frame proximate the horizontal arm, a vertically disposed link connection between the kick-off pedal and toggle breaking arm, a counterbalance weight and a vertical support therefor, a horizontal lever pivoted in the frame under the buck and on one end of which the weight and support is suspended, the other end of said lever being connected with the toggle to urge upwardly thereon, and a link connection interposed between the vertical weight support and upright head support to balance the head in operation. 20
5. In a press, a frame, a buck thereon, a bell crank and an arm integral with the bell crank, a frame pivot on which the arm pivots whereby the bell crank undergoes bodily movement in the frame, a horizontal lever pivoted in the frame below the buck and above the bell crank and connected with the bell crank, force applying means to work the lever to lift the bell crank, an upright pivoted on the bell crank, a press head attached to the upright, and a connection be- 25
6. In a press, a frame, and a buck thereon, a press head, an upright to actuate the head to and from the buck to produce compression, a bell crank pivoted in the frame and on which the upright is pivoted, weight means connected with the bell crank to lift the latter and the head, a connection from the weight means to the upright to counterbalance the head in operation, an upper link above the bell crank and pivoted on the frame and connected with the bell crank forming a vertically disposed toggle, a toggle breaking arm pivoted on the frame and having means to engage the upper link, means to swing the toggle breaking arm, and adjusting means cooperating with the frame pivot of the upper toggle to adjust the degree of compression. 30
7. In a press, a frame and a buck thereon, a press head, an upright to actuate the head, operating means mounted in the frame to support and to work the upright, a vertical link attached to the operating means to urge upwardly on the upright and head, a horizontal lever pivoted in the frame and on one end of which is pivotally connected the vertical link, a horizontal link attached to the upright to apply a lateral force thereagainst, and a vertical support and a weight thereon pivotally hanging from the other end of the horizontal lever and being pivotally connected with the horizontal link. 35
8. In a press, a frame, a buck thereon, a press head, an upright disposed to the rear of the frame and attached to the head to actuate the latter, movable supporting means under the buck on which the upright is pivoted, means to actuate the movable supporting means, and a vertical weight carrying support suspended at the front of the frame and a pendulum weight hung thereon, a link connected between the upright and vertical weight carrying support whereby the weight is drawn rearwardly as the upright swings rearwardly to apply a lateral force to the head. 40
9. In a press, a frame, a buck thereon, a press head, an upright disposed to the rear of the frame and attached to the head to actuate the latter, movable supporting means under the buck on which the upright is pivoted, means to actuate the movable supporting means, a vertical weight carrying support suspended at the front of the frame and a pendulum weight hung thereon, a link connected between the upright and vertical weight carrying support whereby the weight is drawn rearwardly as the upright swings rearwardly to apply a lateral force to the head, a lever pivoted in the frame and on which the vertical weight carrying support is pivotally suspended, and a connection made from the lever to the upright to apply a vertical force to the head. 45
10. In a press, a frame, a buck thereon, an upright attached to the head, movable supporting means below the buck in the frame to operatively support the upright, means to actuate the movable supporting means, a vertically disposed toggle having its upper end pivoted on the frame and its lower end attached to the movable supporting means a lever pivoted in the frame and including a loose motion connection with the toggle, and a weight suspended from the lever adapted to pull downwardly to continuously urge upwardly on the toggle as the latter breaks to lift the head off of the buck. 50
11. In a press, a frame, a buck thereon, an upright attached to the head, movable supporting 55
- 75

- means below the buck in the frame to operatively support the upright, means to actuate the movable supporting means, a vertically disposed toggle having its upper end pivoted on the frame and its lower end attached to the movable supporting means, a lever pivoted in the frame and including a loose motion connection with the toggle, a weight suspended from the lever adapted to pull downwardly to continuously urge upwardly on the toggle as the latter breaks to lift the head off of the buck, and a link connection between the weight and upright to urge laterally on the head as it moves laterally to and from the buck.
12. In a press, a frame, a buck thereon, a press head, an upright to work the head to open and close the press and produce compression, an operating bell crank including a rearwardly extending arm, a frame pivot on which the arm is pivoted to support the bell crank for bodily up-and-down movement in the frame, one portion of the bell crank extending upwardly and a link connected therewith and pivoted on the frame under the buck thereby forming a vertical toggle, said pivot on which the upper end of the vertical toggle is carried also including means for up-and-down adjustment to regulate the compression, a toggle kick-off arm pivoted on the same pivot carrying the upper end of the toggle, a link extending downwardly from the kick-off arm and a pedal connected with the link, a lever pivoted in the frame, a weight hung from the lever, a connection established between the lever and toggle to urge upwardly on the head, means affording relative motion between the lever and toggle, and an interconnection made between the weight and head to apply a lateral force thereon.
13. In a press, a frame and press jaws carried thereon, operating means to actuate one of the jaws and including a toggle, adjustment means for the toggle including a rotary part adapted to move up and down, a notched wheel connected to the part to move the same, and a locking pawl carried on a pivot and having a head engaging the notched wheel to hold the latter to any adjusted position.
14. In a press, a frame, a buck thereon, a press head, and operating means therefor to open, close and produce pressure therebetween, said operating means including a toggle comprising links directly connected one with the other, said

toggle being pivoted on the frame and interconnected with the head, stop means for the toggle including an arm pivoted on the frame and having a slot, and a pin which directly connects the links aforesaid and hence carried with the toggle and engaging the slot, the ends of the slot being adapted to stop the breaking and straightening movement of the toggle by engagement of the pin at first one end of the slot and then the other end thereof.

15. In a press, a frame, a buck thereon, a press head, an upright extending downwardly below the head and buck and having its upper end attached to the head, movable supporting means below the buck and on which the upright swings in the manner of an inverted pendulum, a pendulum weight operatively suspended in the frame, the two pendulums being operatively reversed with the weights acting in opposition to each other, and an interconnection between the two pendulums whereby each pendulum exerts a force against the other, said interconnection being disposed below the pivot of one pendulum and above the pivot of the other pendulum.

16. A garment or ironing press comprising, a frame, a buck thereon, an upright carrying a head, pivot means located adjacent the lower end of the frame and carrying the upright for pivotal and vertical bodily movement, means to operate the upright to open and close the press; and counterbalancing means including a vertical support under the buck swingably mounted at its upper end with respect to the frame and a counterbalance weight on the lower end of the vertical support, and means connecting the counterbalancing means with the upright to counterbalance the pivotal movement thereof.

17. In a press, a frame, and a buck thereon, a press head, an upright carrying the head, a pedal level pivoted to the frame, pivot means carried by the pedal lever adjacent the lower end of the frame and carrying the upright for pivotal and vertical bodily movement, a vertically disposed toggle operatively connected with the pivot means and pivoted on the frame, one of the links of the toggle being integral with the pedal lever, a toggle breaking arm pivoted on the frame and having means to engage the upper link, and means to swing the toggle breaking arm.

JAMES CAMROD LEDBETTER.
